UNITED STATES PATENT OFFICE

CHARLES A. ROWLEY, OF LOS ANGELES, CALIFORNIA

VEGETABLE SHREDDER

Application filed December 18, 1929. Serial No. 415,066.

This invention relates to vegetable and meat-cutters and comminutors, and more especially to an improved type of grater for domestic use.

5 An object of the invention is the provision of an unusually simple and inexpensive shredder, which is possessed of novel, meritorious features such as removability of the shredder plate from the frame of the instrument, to permit its being replaced by a different shredder plate; with the result that several different classes of work may be performed by my improved shredder, by merely selecting and mounting in operative position, 10 the appropriate type of shredder plate.

Another object is the provision of a shredding device in which the shredder plate is removable as described, in which the means for removably mounting the plate upon the frame, are so designed that the selected plate may be substantially instantaneously mounted in operative position upon the plate, and removed therefrom.

The invention possesses other objects and 25 advantageous features, some of which, with those enumerated, will be set forth in the following description of the invention's particular embodiment which is illustrated in the drawings accompanying and forming a part 30 of the specification.

Referring to the drawings:

Figure 1 is a front elevation of a shredding device constructed in accordance with the principles of the present invention.

35 Fig. 2 is a rear elevation.

Fig. 3 is a longitudinal, medial sectional view taken upon the line 3—3 of Fig. 1, with the direction of view as indicated.

Fig. 4 is a front elevation of the frame of 40 the shredder after the shredder plate has been removed.

Fig. 5 is a front elevation of the shredder plate alone.

Fig. 6 is an enlarged, fragmentary, sectional view of a portion of the shredder plate, the plane of section being indicated by the line 6—6 of Fig. 5, and the direction of view by the arrows.

Specifically describing a preferred embodiment of the invention, my shredding de-

vice comprises a frame 11, and a shredding plate 12 adapted to be removably mounted thereupon. The frame 11 is constructed of a suitable length of wire bent in such a manner as to form a pair of opposed, spaced side members 13, which are straight throughout a material length thereof, and which are disposed in parallelism with each other. The side members 13 are retained in spaced relationship by means of a lower end 14, which, as shown upon Fig. 3, is offset from the common plane of the side members 13, being set back therefrom by angular extensions 16 of the side members 13. The side members 13 are retained spaced at their upper ends, 65 through the expedient of a portion 17 of wire extending therebetween, this portion 17 having a loop 18 therein to provide a handle, permitting the frame 11 to be readily and easily retained in convenient operating position by one hand. The handle 18 is deflected so as to extend angularly rearwards from the frame 11, as is also best shown upon Fig. 3. From the base of the handle 18, the portion 17 of the wire, slopes to meet the upper ends 70 of the side members 13 of the frame, so that in effect, the upper end of the frame 11 is pointed, with the handle 18 extending from the point. The frame 11 is also provided with a pair of stops 19, spaced equally from 75 the lower end 14 of the frame and disposed upon the opposed side members 13, these stops being utilized to limit the downward movement of the shredding plate 12 when mounted in operative position upon the 80 frame 11.

The shredding plate 12, a plurality of which, of different types, may be adapted for mounting upon a single frame 11, is in the form of a preferably flat plate 21. This 85 plate 21 is adapted to be easily and removably mounted upon the frame 11, through the expedient of curling the two lateral edges 23 to form flanges 24 extending rearwards from the plate 21, preferably throughout the 90 entire length of the two side edges 23. The plate 21 is of such width that the effective distance between the two opposed flanges 24, corresponds to the width of the frame 11, thereby permitting the side members 13 of 100

the frame 11, to be received within the two flanges 24, as will readily be understood. Furthermore, these flanges 24 are curled so as to substantially conform to the cross-sectional configuration of the wire of which the side members 13 are formed, thus establishing more secure engagement therewith; and each of the flanges 24 is of such dimensions that it extends substantially half way 10 around the associated side member 13. As a result of this construction of the flanges 24, a selected shredding plate 12 may easily be mounted upon, or removed from the frame 11, simply by sliding the plate 12 longitudinally onto the frame 11, with each of the side members 13 of the frame lying within the curvature of one of the flanges 24. The plate 12 should be slid onto the frame 11 from the top end, and the sliding of the plate 20 continued until the bottom edge of the plate engages the stops 19, the parts preferably being so proportioned that when the bottom edge of the plate 12 so engages the stops 19, the upper edge 26 of the plate, which also is 25 preferably pointed, will substantially conform to the upper end of the frame 11.

A flange 27 may be formed upon each of the sloping sides of the upper edge 26, by curling these edges downwards throughout 30 the major portion of their length, in such a manner as to cause the flanges 27 to engage the sloping portions of the upper portion 17 of the wire framework 11. The parts should be so proportioned that the flanges 27 engage 35 the upper portion 17 of the wire framework, at the same time that the lower edge of the shredding plate 12 engages the stops 19; with the result that the stops 19 and the flanges 27, cooperate with each other in retaining the 40 shredder plate 12 in operative position upon the wire frame 11.

The shredding plate 12 is provided with preferably a plurality of cutting edges 31. These cutting edges may conveniently be 45 formed by punching or otherwise forming a plurality of holes 32 in predetermined arrangement throughout the effective area of the plate 21. Preferably, the holes 32 are arranged in rows as illustrated. After the 50 holes 32 have been punched, the material of the plate 21 immediately below each of the holes 32, is pressed toward the front of the plate, i. e., is struck upwards therefrom, so that the lowermost edge of each hole 32, is 55 elevated from the plane of the plate. The edges 31 thus formed, will be relatively sharp because of the fact that as the material of the plate is struck upwards from the plane thereof, it is necessarily stretched to a certain extent, reducing its thickness as compared to the thickness of the remainder of the plate. Preferably, the portion 33 of the plate 21, which is struck upwards below each of the 60 holes 32, corresponds in width to the diameter of the associated hole 32, but is mate-

rially longer, thereby facilitating the passage through the hole 32, of the shred or slice of material which the associated cutting edge 31 has cut.

It is obvious that by supplying a plurality of the shredding plates 12 with their respective holes 32 of different sizes, and with the cutting edge 31 struck upwards different distances from the plane of the respective plates, shreds and/or slices of various thicknesses and width, may be formed.

Each of the plates 12 is reinforced along its lower edge by forming a bead 36 thereon. This may easily be done by simply curling the lower edge over against the rear surface 30 thereof, as shown upon Figs. 2 and 6. Furthermore, each of the plates 12 is provided with an aperture 37 adjacent the upper edge 26 thereof, to facilitate hanging one or a plurality of plates in any convenient location.

Whereas the device is designed primarily for slicing and shredding vegetables, it will readily be appreciated that it may be employed for performing this operation upon 90 a wide variety of materials. It is utilized by supporting the frame 11 with the handle 18 thereof, in one hand, and the offset lower end 14 resting upon a suitable supporting surface 95 which may be the bottom of a bowl or other receptacle into which the shredded material is to fall. The article to be shredded is then reciprocated up and down, in contact with the front face of the shredding plate 12, so that it encounters the various cutting edges 100 31, each of which cuts a shred of material from the article. Each of these shreds passes through the associated hole 32 and falls into the receptacle or onto the supporting surface 105 upon which the frame 11 is supported.

Owing to the relatively large number of cutting edges 31 which may be provided in each of the shredding plates 12, this shredding operation is carried out with the utmost ease and rapidity. The removability of the 110 shredding plates 12 from the frame 11, permits not only the selection of the desired shredding plate to produce shreds of the desired size, but it also materially facilitates 115 cleansing and sterilizing the entire device.

It is to be understood that the details of the invention as herein disclosed, are subject to alteration within the spirit or scope of the appended claims.

I claim:

1. A shredder comprising a wire frame having substantially parallel sides, the upper ends of said sides being brought inwardly toward each other forming a handle, a cutter plate having its side edges bent about half way around the sides enabling the plate to be applied to and removed from the frame by sliding over the inwardly brought upper ends, and means limiting the downward slid- 130

ing movement of the plate relatively to the sides of the frame.

2. A shredder comprising a wire frame having substantially parallel sides, the upper ends of said sides being brought inwardly toward each other forming a handle, a cutter plate having its side edges bent about half way around the sides enabling the plate to be applied to and removed from the frame by sliding over the inwardly brought upper ends, and means limiting the downward sliding movement of the plate relatively to the sides of the frame comprising a rearwardly bent top edge on the plate adapted to engage the inwardly bent portions of the sides.
3. A shredder comprising a wire frame having substantially parallel sides, the upper ends of said sides being brought inwardly toward each other forming a handle, a cutter plate having its side edges bent about half way around the sides enabling the plate to be applied to and removed from the frame by sliding over the inwardly brought upper ends, and means limiting the downward sliding movement of the plate relatively to the sides of the frame comprising stops formed on the sides adjacent the bottom thereof adapted to be engaged by the bottom of the plate.

30 In testimony whereof I have signed my name to this specification.
